UNITED STATES PATENT OFFICE.

GUSTAVE BURKHARDT, OF CHICAGO, ILLINOIS.

LOCKING-SWITCH.

1,181,640.

Specification of Letters Patent.

Patented May 2, 1916.

Application filed January 30, 1915. Serial No. 5,225.

To all whom it may concern:

Be it known that I, GUSTAVE BURKHARDT, a citizen of the United States, residing at Chicago, in the county of Cook and State of Illinois, have invented certain new and useful Improvements in Locking-Switches, of which the following is a specification.

This invention relates to a locking switch particularly adapted to control and lock the electrical circuits of a motor-driven vehicle, although not necessarily limited to such use.

Theft and unauthorized use of motor-driven vehicles may be readily prevented by locking the switch which controls the usual circuits from the battery and magneto to the sparking devices and it is one of the objects of the present invention to provide a switch of relatively simple and inexpensive construction which may be locked in neutral position and which may be released and actuated to close either the battery or magneto circuits by means of a suitable key.

It is a further object of my invention to provide a locking switch in which the key may be withdrawn after the switch has been moved thereby to either of its positions.

It is a still further object of my invention to provide means whereby it is impossible to open the casing inclosing the mechanism without the aid of the proper key.

Other objects and advantages of my invention will appear as it is better understood by reference to the following specification in connection with the accompanying drawing in which—

Figure 1 is a front elevation of the invention; Fig. 2 is a vertical section therethrough; Fig. 3 is a section on the line 3—3 of Fig. 2; Fig. 4 is a rear elevation of the casing; Fig. 5 is a section on the line 5—5 of Fig. 2; Fig. 6 is a detail in perspective of the bridge, and Fig. 7 is a detail in section on the line 7—7 of Fig. 3 of the means for securing the bridge to the base.

Referring to the drawings, 1 indicates a base of suitable form constructed preferably of insulating material. Upon the base 1 a switch arm 2, also of insulating material, is pivotally mounted, the switch arm carrying a knife blade 3 adapted to coöperate at either end with clips 4 and 5 having extensions 6 and 7 mounted upon the base 1, surrounding the binding screws 8 and 9, disposed therethrough. The clips 4 and 5 at either side of the device are connected through suitable wires 10 and 11 with one side of the

battery and magneto circuits, respectively, the wires being disposed about the binding screws 8 and 9 and held in close relation with the extensions 6 and 7 of the clips by washers 12. Upstanding lugs 12' integral with the base 1 prevent lateral movement of the wires 10 and 11 to allow contact thereof with the knife blade 3. The opposite sides of the battery and magneto circuits are connected by wires 13 and 14, respectively, to the binding screws 15 and 16 and therethrough to a plate 17 supported on the base and carrying a clip 18 adapted to engage, at all times, the knife blade 3. The clip 18 is provided with a lug 19 which coöperates with an opening 20 in the knife blade 3 to indicate the neutral position of the knife blade 3 in which position it engages neither of the clips 4 and 5.

Surrounding the binding screws 8 and 9 above the washers 12 are insulating collars 21 which support the feet 22 of the bridge 23. The feet 22 are provided with bifurcated ends 24, which are adapted to be bent around the collars 21, as indicated in Fig. 3, when the device is assembled, to rigidly hold the bridge in its proper position, the bridge being insulated by the collars 21 from the binding screws 8 and 9. The bridge 23 comprises a circular plate having a circular opening 25 and radiating openings 25' therein, corresponding in general form to a cross.

A metallic casing 26 of suitable form is adapted to be mounted upon the base 1 and held in proper relation therewith by screws 27 passing therethrough and into threaded sleeves 28 in the lugs 29, integral with the base. The casing 26 is provided with inwardly extending pins 26' which coöperate with the lugs 29 of the base 1 to prevent relative angular movement of the base 2 in the casing 26. A lock 30 of the cylinder type comprising a rotatable cylinder 31 and spring-actuated plungers 32, operable by a key 33 to release the cylinder 31, is mounted in the casing 26, a collar 34 being threadedly mounted on the lock beneath the casing 26 to rigidly hold it in coöperative relation therewith.

A spindle 35, having a flange 36, is secured by means of screws 37 to the inner end of the lock cylinder 31 and projects inwardly through a central opening in the switch arm 2. A switch actuating member 37 is loosely journaled upon the spindle 35 and prevented from longitudinal movement thereof by engagement with the shoulder 38

on the spindle and by a suitable fastening means 39 at the end of the spindle. The switch-actuating member 37 is provided on one side with inwardly extending lugs 40 engaging suitable notches in the switch arm 2 and on its opposite side with a lug 41 adapted to engage a lug 42 on the flange 36 of the spindle 35.

The central portion of the switch actuating member 37 is circular in form and of substantially the same diameter as the opening 25 in the bridge 23 and is provided with laterally extending arms 43 of the same configuration as the radial openings 25' in the bridge 23, these arms being adapted, as clearly shown in Fig. 2, to engage beneath the bridge, whereby the casing 26 may be locked in proper relation to the base 1 irrespective of whether screws 27 are in position or not.

The operation of the device will, it is thought, be apparent without further description of the structure thereof. The mechanism is assembled by moving the switch arm 2 until it contacts with the abutment formed by lug 29 at the left of Fig. 3, whereupon the knife blade 3 engages the clip 4, closing the battery circuit. With the lock cylinder in key-removing position as indicated in Fig. 1, the switch actuating member 37 is turned as far as possible in a clock-wise direction, viewing Fig. 4, in which position the arms 43 will register with the openings 25' in the bridge 23 and the casing 26 may be mounted in proper position upon the base 1. By inserting the key 23 and turning the lock cylinder 31 in a clock-wise direction, viewing Fig. 1, the arms 43 of the switch-actuating member 37 are moved out of register with the openings 25' and the casing 26 is thereby held rigidly to the base 1, the casing being prevented from angular movement relative thereto by the pins 26'. The screws 27 are then inserted to provide additional holding means for the casing. The structure being assembled, the switch arm 2 may be moved in either direction by the key 33, to engage the knife blade 3 with either of the clips 4 or 5 to close the battery or magneto circuits, or the switch arm 2 may be moved to neutral position with the lug 19 on the clip 18 engaging the opening 20 in the knife blade 3. The marks on the face of the lock, as shown in Fig. 1, indicate the position of the key when the knife blade 3 is in engagement with either of the clips 4 or 5 or in neutral position. The lugs 41 and 42 on the switch-actuating member 37 and the flange 36 of the spindle 35, respectively, form a lost motion connection between the lock cylinder 31 and the switch-actuating member 37, the lost motion being substantially equal to a half revolution of the lock cylinder 31, and it will be apparent that by reason of the lost

motion connection the lock cylinder 31 may be returned to the key-removing position, as shown in Fig. 1, after the knife blade 3 has been moved to either of its positions and without disturbing the position of the knife 70 blade. This is a particularly advantageous feature of my invention since the operator frequently carries the key attached to others and it is not desirable to have the key remain in the lock while the vehicle is in operation. 75

To dismount the casing 26 from the base 1 it is necessary only to remove the screws 27, insert the key and turn the switch until the knife blade 3 engages the clip 4, in which 80 position the arms 43 register with the openings 25' and the casing 26 may be lifted from the base 1. It is obvious, of course, that while I have described a particular arrangement of the arms 43 and the openings 85 in the bridge 23 the parts may be arranged to register upon turning the switch-actuating member 37 to any definite position. The battery-circuit closing position is the position least used and one in which the switch 90 would not ordinarily be left and it will be readily seen that unless the knife blade is in engagement with the clip 4, in the embodiment shown in the drawings, access to the mechanism can not be had by mere removal 95 of the screws 27 and hence tampering with the mechanism is impossible unless a key of proper configuration is available.

It will be apparent that various changes 100 may be made in the form, construction and arrangement of the parts without departing from the spirit and scope of the invention or sacrificing any of its material advantages, the form hereinbefore described being merely a preferred embodiment thereof. 105

I claim:

1. In a device of the character described, the combination of a base, a switch mounted thereon, a lock comprising a rotatable cylinder and key controllable means to normally prevent rotation thereof, a flanged spindle secured to said cylinder, switch actuating means journaled on said spindle, and cooperating means on said switch-actuating means and the flange of said spindle 115 providing a lost motion connection therebetween.

2. In a device of the character described, the combination of a base, a switch mounted thereon, a lock comprising a rotatable cylinder and key controllable means to normally prevent rotation thereof, a flanged spindle secured to said cylinder, switch actuating means loosely journaled on said spindle, and cooperating lugs on said switch-actuating means and the flange of said spindle 120 providing a lost motion connection therebetween.

3. In a device of the character described, the combination of a base, a switch mounted 125

- thereon, a casing, a lock secured to said casing and comprising a rotatable cylinder and key controllable means to normally prevent rotation thereof, a flanged spindle secured to 5 said cylinder, means journaled on said spindle having lugs thereon adapted to engage and actuate said switch, coöperating means on said switch actuating means and the flange of said spindle providing a lost motion connection therebetween, and coöperating 10 means on said base and switch actuating means to prevent removal of said casing except when said switch-actuating means is disposed in a predetermined angular position. 15
4. In a device of the character described, the combination of a base, a switch mounted thereon, a casing, a lock secured to said casing and comprising a rotatable cylinder and 20 key controllable means to normally prevent rotation thereof, a flanged spindle secured to said cylinder, means journaled on said spindle having lugs thereon adapted to engage and actuate said switch coöperating 25 means on said switch actuating means and the flange of said spindle providing a lost motion connection therebetween, coöperating means on said base, and switch-actuating means to prevent removal of said casing except when said switch-actuating means is disposed in a predetermined angular position, screws securing said casing to said 30 base and coöperating means on said base and casing to prevent relative angular movement therebetween. 35
5. In a device of the character described, the combination of a base, a switch mounted thereon, a casing, a lock secured to said casing and comprising a rotatable cylinder and 40 key controllable means to normally prevent rotation thereof, a flanged spindle secured to said cylinder, switch actuating means journaled on said spindle, coöperating means on said switch actuating means and the 45 flange of said spindle providing a lost motion connection therebetween, supports on said base, a bridge detachably secured to said supports, and coöperating means on said bridge and switch actuating means, whereby removal of said casing is prevented except when said switch actuating means is disposed in a predetermined angular position. 50
6. In a device of the character described, the combination of a base, a switch mounted 55 thereon, a casing, a lock secured to said casing and comprising a rotatable cylinder and key controllable means to normally prevent rotation thereof, a flanged spindle secured to said cylinder, means journaled on said spindle having lugs thereon adapted to engage and actuate said switch, coöperating means on said switch actuating means and the flange of said spindle providing a lost motion connection therebetween, supports 60
- 65

on said base, a bridge detachably secured to said supports, coöperating means on said bridge, switch actuating means to prevent removal of said casing except when said switch actuating means is disposed in a predetermined angular position, screws securing said casing to said base and coöperating means on said base and casing to prevent relative angular movement therebetween. 70

7. In a device of the character described, the combination of a base, a switch mounted thereon, a casing, a lock secured to said casing and comprising a cylinder and key controllable means to normally prevent rotation thereof, supports on said base, a bridge detachably secured to said supports and spanning said switch, and means connected to said cylinder and coöperating with said bridge to prevent removal of said casing except when said cylinder is moved to a predetermined angular position. 75

8. In a device of the character described, the combination of a base, a switch mounted thereon, a casing, supports on said base, insulating collars on said supports, a bridge mounted on said supports and insulated therefrom by said collars, and means connected to said casing and coöperating with said bridge, whereby removal of said casing is prevented except when said means is disposed in a predetermined angular position. 80

9. In a device of the character described, the combination of a base, a switch mounted thereon, a casing, supports on said base, insulating collars on said supports, a bridge mounted on said supports and insulated therefrom by said collars, means rotatably connected to said casing and coöperating with said bridge, whereby removal of said casing is prevented except when said means is disposed in a predetermined angular position, and coöperating means on said base and casing to prevent relative angular movement therebetween. 95

10. In a device of the character described, the combination of a base, a switch mounted thereon, comprising a member movable to neutral and to circuit closing positions, a casing, a lock mounted in said casing and comprising a rotatable cylinder and key controllable means to normally prevent rotation thereof, a key insertible at one angular position of said cylinder, a flanged spindle secured to said cylinder, switch actuating means rotatably mounted on said spindle, and coöperating means on said switch actuating means and the flange of said spindle providing a lost motion connection, whereby upon rotation of said cylinder by said key said switch member may be moved to either of its positions, and said cylinder returned to withdraw the key therefrom without disturbing the position of said switch member. 115

11. In a device of the character described, 120

the combination of a base, a switch mounted thereon, a casing, a lock secured to said casing and comprising a cylinder and key-controllable means to normally prevent rotation thereof, supports on said base, insulating collars on said supports, a bridge mounted on said supports and insulated therefrom by said collars, and means connected to said cylinder and coöperating with said bridge, 10 whereby removal of said casing is prevented except when said means is disposed in a predetermined angular position.

12. In a device of the character described, the combination of a base, a switch mounted 15 thereon, a casing, a lock secured to said casing and comprising a cylinder and key-con-

trollable means to normally prevent rotation thereof, supports on said base, insulating collars on said supports, a bridge mounted on said supports and insulated therefrom by said collars, said bridge being provided with an opening, and means connected to said cylinder and providing laterally extending arms adapted to pass through said opening and engage beneath said bridge, 20 whereby removal of said casing is prevented except when said arms are disposed in a predetermined angular position. 25
